[57] CLAIM

I claim the ornamental design for a measuring canister, as shown and described.

DESCRIPTION

FIG. 1 is a top plan view of a measuring canister showing my new design;

FIG. 2 is a side elevation view thereof, the opposite side being identical;

FIG. 3 is a rear elevation view thereof;

FIG. 4 is a front elevation view thereof;

FIG. 5 is a bottom plan view thereof;

FIG. 6 is a perspective view thereof; and,

FIG. 7 is a perspective view thereof in an open position.
